[57] CLAIM

The ornamental design for a waste collection tool, as shown and described.

DESCRIPTION

FIG. 1 is a perspective view of a waste collection tool showing my new design.

FIG. 2 is a front elevational view thereof.

FIG. 3 is a rear elevational view thereof.

FIG. 4 is a right side elevational view thereof, the left side view being a mirror image of the right side view.

FIG. 5 is a top plan view of the waste collection device; and, FIG. 6 is a bottom plan view thereof.

The broken lines are for purposes of illustration only and forms no part of the claimed design.
